ROCKEL ALEXANDER FRITSCH, OF CHICAGO, ILLINOIS, ASSIGNOR TO JOHN LAWRIE, OF CHICAGO, ILLINOIS

FOUNTAIN PEN

Application filed November 17, 1928. Serial No. 148,976.

This invention relates to an improvement in fountain pens, and aims to provide a fountain pen which is so organized and constructed as to make possible the filling of the pen in a simple, positive and efficient manner and which provides a pen of relatively large capacity.

Another object is to provide a fountain pen which has these advantages and capacities and wherein the parts of the pen may be adjusted to take up wear or may be replaced with facility.

A further object is to provide a fountain pen of this character which is simple and durable in construction, reliable and efficient in operation, and easy and comparatively inexpensive to manufacture.

Other objects and advantages reside in certain novel features of the construction, arrangement and combination of parts which will be hereinafter more fully described and particularly pointed out in the appended claims, reference being had to the accompanying drawings forming a part of this specification, and in which:

Figure 1 is a view in longitudinal central section showing a fountain pen constructed in accordance with the present invention,

Figure 2 is a similar view of another form of the invention,

Figure 3 shows a slight variation of the form of the invention illustrated in Figure 2,

Figure 4 is a view in central longitudinal section showing another embodiment of the invention,

Figure 5 is a view in transverse section taken on the line 5—5 of Figure 4.

Figure 6 is a sectional view similar to Figure 5 but showing the different position of the parts, and

Figure 7 is a fragmentary detail view in central longitudinal section further illustrating the feed plug shown in Figure 4.

Referring to the drawings and more particularly to Figure 1 it will be seen that the present invention proposes a fountain pen having a barrel 1 having its forward end provided with an internal enlargement at 2 in the longitudinal opening or bore 3 of which a feed plug 4 is fitted and frictionally held

or otherwise suitably secured. The feed plug 4 also serves to carry a pen point 5 which has an opening 6 therein. The pen 5 overlies a groove 7 provided in one face of the plug 4, the groove 7 extending rearwardly to a transverse passage 8 which serves to establish communication between the groove 7 and an opening 9 formed in the plug 4 and extending from a point adjacent its forward end out through the rear end of the plug. An outer tube 10 is provided within the barrel 1 and has its forward end threaded or otherwise suitably connected with the rearward end of the wall of the opening 9 of the plug 4, the threaded connection between the tube 10 and plug 4 being indicated at 11. As indicated in Figure 1 the outer tube 10 extends axially through the barrel 1 for a substantial portion of the length of the barrel. An inner tube 12 is slidably fitted in the outer tube 10 and has its rearward end suitably secured to a head 13 threaded or otherwise fastened to a sleeve 14. The sleeve 14 is slidably fitted on the barrel 1 and may be held against turning movement in any suitable way. The head 13 is provided with inclined openings 15 which meet just inwardly of the rear end of the inner tube 12 to define an enlarged space 16. The openings 15 and space 16 provide for communication between the rear end of the tube 12 and the interior of the barrel 1. Communication between the interior of the tube 12 and the interior of the barrel 1 is also had through openings 17 and slots 17^a here shown formed in the rear end portion of the tube 12. In order to provide a fluid tight connection between the sleeve 14 and the barrel 1 a plurality of rubber packing rings 20 are provided and are confined between rigid rings 21 of metal or other suitable material, the rings 21 being threaded or otherwise connected with the barrel 1 and being adjustable will compress and expand the rubber rings 20 to the desired extent. In order to prevent accidental displacement of the sleeve 14 a retaining band 22 is provided and is threaded or otherwise connected to the forward end of the sleeve, as indicated at 23. This band 22 is engageable with the forward end ring 21 when the sleeve 14 has been

55

60

65

70

75

80

85

95

100

10 pulled rearwardly as far as it may be. In order that all of the ink may be used or in other words in order to prevent the ink from being trapped in the barrel 1 the inner tube 12 is provided with an arcuate groove 12^a and the outer tube 10 is provided with a similar arcuate groove 10^a, the grooves 10^a and 12^a registering when the parts of the pen are in operative or writing position, as illustrated in Figure 1.

15 It is to be understood that the barrel 1 of the pen, its feed plug 4, its tubes 10 and 12, its sleeve 14, the head 13 of the sleeve and the retaining band 22 are all constructed of rigid material which may be a hard rubber compound or of metal or any other suitable hard and rigid substance.

20 In filling the pen the point is immersed in the ink so that the opening 6 of the pen point is covered. This is done when the parts of the pen are positioned as shown in Figure 1. The barrel 1 is then held and the sleeve 14 is pulled rearwardly. This increases the internal area of the barrel of the pen since the 25 sleeve 14 by being pulled rearwardly with respect to the barrel 1 has its opening in communication with the opening of the barrel. The rarefaction or suction which occurs pulls the ink in through the opening 6 along the 30 groove 7, through the passage 8 and into the tube 12, the ink flowing from the tube 12 into the barrel 1 through the openings 17 and slots 17^a and through the space 16 and holes 15. It is to be noted that when the sleeve 14 is 35 pulled rearwardly it carries with it the tube 12 and as the tube 12 is moved relative to the tube 10 the slots 10^a and 12^a are moved out of register at the very start of the filling operation. After the sleeve 14 has been pulled 40 rearwardly as far as it may be, it is then advanced slowly forward which expels the excess air from the pen without pushing out any material quantity of ink. This operation of moving the sleeve 14 back and forth should 45 be repeated several times to entirely fill the pen. When the air escapes from the pen on the forward movement of the sleeve 14 it passes through the openings 17 and slots 17^a and through the holes 15 and space 16 into 50 the tube 12 and thence out through the passages in the feed plug. It does not pass through or tend to displace the main quantity of ink which is trapped in the barrel 1 since the slots 10^a and 12^a are out of registry.

55 In the form of the invention shown in Figure 2 the pen has a barrel 30 having at its forward end an opening 31 which receives a feed plug 32. Rearwardly of the opening 31 an internal flange 33 is provided. The feed 60 plug 32 carries a pen point 34 having the usual openings 35 and the pen 34 overlies a longitudinal groove 36 provided in the periphery of the feed plug, the groove 36 extending rearwardly of the plug 32 to its rear 65 end. As shown in the drawing the rear end

70 of the plug 32 is spaced from the adjacent face of the flange 33 to provide an ink space 37. The ink space 37 is in open communication with the axially extending opening 38 of the feed plug, the opening extending from a point adjacent to but spaced from the forward end of the feed plug out through the rear end thereof. A single axially extending tube 40 is provided and has a snug though sliding fit in the opening of the flange 33, or a bushing, 33^a similar to #63 in Fig. 3, in such flange. The tube 40 extends up into opening 38 of the feed plug in certain phases of the filling operation and the forward end of this tube is provided with an arcuate slot 41 which in the writing position of the parts lies just rearwardly of the flange 33. The rearward end of the tube 40 is threaded or otherwise connected, as indicated at 42, to a head 43 threaded or otherwise connected, as at 44, to the rear end of a sleeve 45 which is slidably fitted on the barrel 1. The sleeve 45 may be releasably secured in either one of its extreme positions by interengaging threads 46 on its sleeve with threads 47 or 48 provided on the barrel. In order to provide a fluid tight connection between the sleeve 45 and the barrel, the barrel has an externally threaded tube 49 connected with its rear end and on this tube a plurality of rubber rings 50 are mounted, the rubber rings 50 being confined by metallic or other firm rings 51 threaded or otherwise connected with the tube 49 and being expanded in this way as much as necessary to cause them to have the proper packing engagement with the sleeve 45. These rubber rings and firm metal rings present the same broad packing construction as illustrated in Fig. 1 but as is now apparent the construction shown in Fig. 2 mounts these rings on a separate tube rather than directly on the barrel. At this point it is also to be noted that the feature of releasably securing the sleeve in either of its extreme positions by engaging threads on the sleeve with threads on the barrel might be practiced to advantage with the form of the invention shown in Figure 1. The single tube 40 employed in the form of the invention shown in Fig. 2 has at its rearward end 100 openings 40^a and slots 40^b to provide for communication between the interior of the tube 40 and the interior of the barrel 30. In filling the fountain pen shown in Figure 2 the air is expelled from the pen as much as it may be by advancing the sleeve 45 on the barrel 30 105 to the position indicated in Fig. 2. The pen point is then immersed in ink until the opening 35 is covered and the sleeve 45 is then moved rearwardly along the barrel 30 and ink is pulled in through the opening 35 of the pen point through the slot 36, space 37, tube 40 from whence it flows through the opening 40^a 110 and slots 40^b into the barrel 30. The back and forward movement of the sleeve 45 may be repeated as often as it is necessary to cause 115

120

125

130

a full charge of ink to be drawn into the barrel 30.

Figure 3 illustrates a slight variation of the form of the invention shown in Figure 2. In Fig. 3 the barrel has at least its forward end constructed in accordance with the barrel in Fig. 1; that is, the barrel of Fig. 3 which is indicated at 60, has an opening 61 to receive the feed plug 62. The feed plug 62 is, however, constructed like the feed plug 32 illustrated in Fig. 2 with the exception that it completely fills the opening 61 and has its rearward end exposed to the interior of the barrel. The feed plug 62 also has a bearing and packing plug 63 threaded thereinto and in this plug 63 the tube 40 is slidably fitted. By this construction the flange 33 is omitted and is replaced by the barrel 60.

In the form of the invention shown in Figs. 4 to 7 the pen comprises a barrel 75 having a feed plug receiving member 76 at its forward end. In the member 76 a feed plug 77 is fitted and frictionally or otherwise suitably secured. The feed plug 77 carries the pen point 78 having the usual opening 79 and this pen point 78 overlies the longitudinal groove 80 extending rearwardly to a transverse passage 81 which communicates with an axial opening 82 formed in the feed plug and extending from a point intermediate the length thereof out through the rear end of the same. The rear end portion of the feed plug is also provided with a radial slot 83 which affords communication between the barrel and the opening 82 in certain adjustments of the parts of the pen as will hereinafter be more fully described. A single axially extending tube 84 is provided and has its forward end rotatably fitted in the opening 82 of the feed plug. The forward end of this tube 84 is open and adjacent its forward end the tube 84 has a longitudinal slot 85 which may be brought into registry with the slot 83 or moved out of registry therewith, as indicated in Figs. 5 and 6, respectively. The rear end of the tube 84 is threadedly connected or otherwise suitably fixed to a head 86, the head 86 being threadedly connected or otherwise suitably fastened to a sleeve 87, the latter being rotatably mounted on the barrel 75 and being constrained to rotary movement by means of a lug or rib 88 fitting in an arcuate groove 89 provided in the sleeve 87. The arcuate groove 89 has an angular extent sufficient to enable the sleeve 87 to be turned relative to the barrel 75 as may be necessary to carry out the operation. The end walls of the groove 89 engage the rib or lug 88 to limit the extreme movements of the parts. As shown the rearward end portion of the tube 84 is provided with a plurality of openings 90 affording communication between the interior of the tube 84 and the interior of the barrel 75. An elastic or rubber tube or cylindrical

member 91 is provided and has one end fastened to a collar 92 formed on the barrel 75 and has its other end fastened to a collar 93 formed on the head 86. This tube 91 has sufficient elasticity to normally maintain its expanded cylindrical form shown in the drawings but it is sufficiently yieldable to be collapsible upon twisting thereof and such twisting occurs when the sleeve 87 is turned relative to the barrel 75.

In filling the pens shown in Figs. 4 to 7 the sleeve 87 is turned relative to the barrel 75 to twist the elastic tube 91, thereby collapsing the tube 91 and expelling the air. The pen with the parts so adjusted then has its point 78 immersed in the ink so that the opening 79 is covered. The sleeve 87 is then permitted to resume its normal position or is turned to untwist the tube 91, thereby permitting the tube 91 to expand and draw the ink in through the opening 79, groove 80, passage 81, opening 82, tube 84 and openings 90. As in the other embodiments of the invention at the start of the air-expelling phase of the operation the supply of ink in the barrel is cut off from the pen. In this instance this result is accomplished by virtue of the fact that the slot 85 moves out of registry with the slot 83. The advantage of this feature resides in the fact that the air which occupies the upper portion of the barrel is expelled without expelling the ink which is trapped in the lower end of the barrel. However, as soon as the pen has been completely filled all of the ink in the barrel may be used since none is trapped when the parts of the pen are in writing position.

I claim:—

1. A fountain pen comprising a barrel, a feed plug at the forward end of the barrel, a sleeve movably mounted on the rear end of the outer face of the barrel, a tube having its rear end connected to the sleeve and having its forward end provided with a slot, the slot in the forward end of the tube permitting the ink in the lower end of the barrel to pass into the feed plug in the writing position of the parts, and means on the feed plug and co-operable with the slotted portion of the tube for closing the slot and trapping the ink in the pen when the sleeve is moved to expel the air from the pen.

2. A fountain pen comprising a barrel, a feed plug at the forward end of the barrel, a sleeve slidably fitted on the rearward end of the outer face of the barrel, a tube carried by said sleeve having its forward end co-operable with the feed plug, said forward end being provided with an arcuate slot, and an outer tube connected to the feed plug and having a slot registering with the slot of the first-mentioned tube when the parts are in writing position, the slots being out of registry when the parts are moved to fill the pen.

3. A fountain pen comprising a barrel, a feed plug at the forward end of the barrel, a sleeve slidably fitted on the rearward end of the outer face of the barrel, a tube having its rearward end fixed to the sleeve and having its forward end co-operable with the feed plug, said forward end being provided with an opening, said barrel having an internal bushing snugly engaged with the tube, the opening of the tube when on one side of the bushing permitting the ink to feed from the lower end of the barrel to the feed plug and when on the other side of the bushing trapping the ink in the barrel. 70
4. A fountain pen comprising a barrel having a feed plug at its forward end, a sleeve fitted on the outer face of the barrel, a tube having its rearward end connected to said sleeve, the rearward end of the tube having an opening, the forward end of the tube opening into the feed plug, the feed plug being communicable with the interior of the barrel through said tube and opening and communicable with the tube when the parts of the pen are in writing position. 80
5. A fountain pen comprising a barrel, a feed plug at the feed end of the barrel, a sleeve slidably fitted on the outer face of the rearward end of the barrel, packing means between the barrel and the sleeve, a tube having its rearward end connected to the sleeve, and having openings adjacent its rear end, the forward end of the tube being co-operable with the feed plug and having a slot permitting the ink to flow from the lower end of the barrel to the feed plug, and means co-operable with the slot for closing the same when the air is being expelled from the pen prior to the filling. 90
6. A fountain pen having a barrel, means for conducting fluid to and from the barrel associated with the barrel, means operable on the outer face of the barrel to produce a suction in the barrel and also operable to expel air from the barrel, and means for trapping the ink in the lower portion of the barrel when said means is operated to expel air from the barrel. 100
7. A fountain pen having a barrel, a feed plug at the forward end of the barrel, means operable on the outer face of the barrel to produce a suction in the barrel through the feed plug and also operable to expel air from the barrel, and means on the feed plug and co-operable with said last mentioned means for trapping the ink in the lower portion of the barrel when said means is operated to expel air from the barrel. 110
8. A fountain pen comprising a barrel, a feed plug at the forward end of the barrel, a movable operating element mounted on the outer face of the barrel and a tube connected with the operating element, said feed plug and said tube having cooperating means to permit the ink in the lower end of the barrel to pass to the feed plug in the writing position of the parts and to trap the ink in the lower part of the barrel when filling the pen and expelling air therefrom. 120
9. A fountain pen comprising a barrel, a feed plug at the forward end of the barrel, a sleeve movably mounted at the rear end of the outside of the barrel, a tube connected to the sleeve and extending through the barrel, said feed plug having an opening in which the forward end of the tube is receivable, the tube having openings in its rearward portion, said tube having a slot in its forward portion, and means co-operable with the slot to control the communication of the lower end of the barrel with the feed plug. 130
10. In a fountain pen, a reservoir composed of two tubular main sections telescopically engaged, a pen point mounted in the front of the forward section the rear portion of said forward section forming a piston in the forward part of the rear section which is closed at its rear end, a small inner tube corresponding in length substantially to the length of the two sections and carried at its rear end by the closed rear end of the rear section, said tube having openings therein and the forward section having a restricted opening to receive the front end of said inner tube. 140
11. A fountain pen having a barrel, a feed plug at the forward end of the barrel and having an open portion, a tube movably extending into the feed plug and having communication therewith, said tube being open to the interior of the barrel at its upper end, said tube having an opening at its lower end, and means carried by the barrel and carrying the tube being operable to shift the tube for closing said opening at the lower end thereof when said means is moved to expel air from the upper portion of the barrel through said tube and said plug. 150
12. A fountain pen comprising a barrel having a pen point in one end and its other end open, a sleeve movable on said barrel over said open end for closing the same, a feeding and filling tube affixed to said sleeve and movable therewith, said tube cooperating with means formed in the point end of said barrel for opening communication between the interior of said barrel and said point in the writing position of said parts and for closing such communication during the major portion of the filling operation, said tube providing means through which ink may be drawn into said barrel from said point end. 160
13. A fountain pen comprising a barrel, a pen point associated with the barrel, a sleeve operable on the outer face of the barrel, said sleeve being movable for alternate reduction and expansion of the interior volume 170

of said barrel, and cooperating means carried by said sleeve and barrel operable throughout substantially the entire cycle of said motion for trapping ink in said barrel so long as air remains therein to be expelled by reduction of volume of said barrel.
